UNITED STATES PATENT OFFICE.

WILLIAM A. WEBSTER, OF GALESBURG, ILLINOIS, ASSIGNOR OF ONE-HALF TO JOHN HULSE, OF GALESBURG, ILLINOIS.

SACK-BALER.

1,135,931.

Specification of Letters Patent. Patented Apr. 13, 1915.

Application filed August 18, 1914. Serial No. 857,392.

To all whom it may concern:

Be it known that I, WILLIAM A. WEBSTER, a citizen of the United States, and a resident of Galesburg, in the county of Knox and 5 State of Illinois, have invented a new and useful Sack-Baler, of which the following is a specification.

My improvements relate more particularly to devices for baling cement, salt, and other sacks with wire, and for securing the ends of the bale-wire together after the bale is completed. It will be evident, however, as the nature of the invention is more fully disclosed and better understood, that the improvements are of such nature that they 10 may readily be utilized for baling bundles of angle and other irons, ax, fork and other handles, and for a great many other purposes too numerous to here recite. By a slight modification the improvements may 15 readily be converted into a shock binder and wire-tier.

In the accompanying drawings: Figure 1 is a perspective view of a baler embodying 20 my improvements; Fig 2, an end elevation; Fig. 3, a fragmental top plan, illustrating a somewhat modified arrangement of the wire-twisting and tightening devices and of the method of baling; Fig. 4, an edge elevation 25 of the knotting mechanism; Fig. 5, a vertical central sectional detail in Fig. 4; Fig. 6, a detail, a rear elevation; Fig. 7, a modification, an edge elevation; Fig. 8, a front elevation of the parts shown in Fig. 7; Fig. 9, 30 an inner end view of the sack-counting mechanism; and Fig. 10, a side elevation thereof. Figs. 4 to 10 inclusive are greatly enlarged with reference to Figs. 1 to 3.

Coming now to a detailed description of 35 the drawings, and referring to each element and where necessary to each part thereof by a distinguishing numeral, uniformly employed, 2 designates a floor on which are secured the legs 3 of a table of which 4 indicates the top.

5—5 are L-shaped standards, of which there are preferably three, each of which is bolted to the top 4. The upper end of each standard is bifurcated and provided with 45 transversely arranged registering apertures for a purpose presently recited. Inasmuch as these standards and the mechanism associ-

ated therewith are duplicates, each of the others, it will be necessary to describe but one.

6 designates a socket or ring-head having a radially arranged slot 7 communicating with its axial bore 8. It is provided with a foot 9 having a curved lower corner, and with a transverse opening for the reception 55 of a bolt 10 which passes through the registering openings earlier herein referred to, whereby the head is pivotally mounted in the top of the standard, for a purpose presently described.

11 designates a crank arm having at one end a handle 12 and at its other end a wire-twisting hub 13 provided with an axially arranged countersunk pocket 14 and with a radial slot 15 which at its heel extends to 60 the distant side of the pocket. A wire-engaging pin 16 is cast or otherwise secured to the heel 18.

In the modification shown in Figs. 7 and 65 8 I have shown a hand piece 19 provided with a socket or ring-head 22 corresponding to the head 6 except that the slot is arranged in the end instead of in the side. 20 designates a long pin secured on the inner face of the hand piece and projecting at a right 70 angle thereto.

In operation, the sacks 23 are laid on the 75 table top 4, upon which the baling wires 21 have previously been placed. One end portion of the wires is then looped around the 80 sacks and both ends then passed through the slots 7 and 15, which have been brought into registration, and one or both the ends of the wire bent over the pin 16. Rotations of the crank handle will cause the hub 13 to 85 intertwist the wires as shown in Fig. 4. If continued for a sufficient length of time they will be severed, substantially at the shoulder 90 26, by the extreme tension. The ends of a pair of wires may be spliced or intertwined 95 in a similar manner, it being necessary, however, to hold corresponding ends thereof by means of a pair of pliers.

In Fig. 2 a completed bale is shown, its 100 initial position being indicated by the dotted lines. From this view it will be seen that the pivoted head 6 will swing on its fulcrum to automatically accommodate itself to the varying directions in which the wires enter

- it and the hub in the operation of baling. These conditions are especially noticeable, however, when baling small bundles, such as lengths of angle irons, handles, etc., etc. The 5 plane bottom portion 9' of the foot 9 rests on a plane portion 9" of a seat intermediate the ears 5' at the top of the standard, and prevents the head from tilting in one direction from its vertical and normal position. 10 In order that there will be no sharp projecting corners to sever the wires I have countersunk the outer end of the opening 14 as shown clearly in Fig. 5.

In Fig. 3 I have shown the sacks as having been placed upon the table after being doubled upon themselves, end to end. In this view the wire tighteners and twisters are placed one at the side and one at the end of the table, and the wires cross each at right 20 angles on the bale.

The device shown in Figs. 7 and 8 may easily be carried about and is adaptable as a hand baler for any of the purposes or uses to which the type of device shown in 25 the principal figures may be applied. However, this modified type may be more conveniently used by telegraph and telephone linemen, fence builders and others engaged in kindred lines of work, for tying small 30 bundles, and for a vast number of other purposes for which a non-portable one would not answer. Chief among these may be mentioned its adaptability as a corn (or other) shock binder and tier. When used 35 for this purpose the pin 20 is stuck into the shock to support the hand piece while the operator carries the wire around the shock, whereupon the tightening and twisting operation is proceeded with in the manner above described. Inasmuch as the entire device is free to turn in any direction it is unnecessary to provide it with a pivoted 40 head.

Cement sacks being relatively valuable, 45 are carefully counted when being baled for return to the mill. Inasmuch as they are usually placed on the table one by one, and baled in bundles of fifty, the operator very often miscounts them, whereby the owner 50 (shipper) is "docked" by the mill for shortage, or else he (the operator) loses track of the count and therefore has to recount them. In fact, it has been the practice not only to count them as they are placed on the 55 table, but to recount them before the wires receive final placement. Each of these methods is very unsatisfactory. Therefore, in order that the count may be accurate and without an effort on the part of the operator to constantly memorize it I have 60 provided the table with a very simple and convenient form of counter, shown best in Figs. 9 and 10, wherein 27 designates a supporting bracket having an internally 65 threaded hub 28. 29 indicates a count-screw,

provided with a fixed number of threads adapted to engage those in the hub 28. 30 designates a head on one end of the screw. 31 indicates a count wheel on the other end thereof, the number of its spokes having a 70 predetermined relationship to the number of threads on the screw 29. 32 is a spring detent.

In operation, as the operator places each sack on the table (or on a previously laid 75 sack) he will give a part-revolution to the click or count wheel, the extent of movement being one spoke over the detent, which of course prevents backward movement of the wheel. He need not watch the wheel, 80 for the sound of the spring slipping off the spoke will be plainly audible. The number of threads on the screw, should the count wheel have four spokes, would be equal to one-fourth the number of sacks 85 which it is desired to place in each bundle, so that when the head 30 and wheel 31 have been given a complete rotation four sacks would have been placed on the stack, and when the screw has been turned as far forward as is possible, an accurate count of the sacks will have been made without mental effort on the part of the operator.

In the drawings forming a part hereof all my improvements have been embodied 95 in the best way now known to me; obviously, however, some of these constructions may vary in details from those shown, and some may be used without the others, without departing from the spirit and scope of 100 my invention.

I claim as new and desire to secure by Letters Patent the following, namely:—

1. In a baler, a table, and a plurality of wire-twisting and tightening devices mounted thereon, a portion of said devices arranged at right angles to each other.

2. In a device of the character described, a standard, a head pivoted thereon, and wire-twisting means working in said head.

3. In a device of the character described, a standard having ears at its upper end, a slotted ring-head pivoted between said ears, and a slotted wire-twisting hub rotatably mounted in said hub.

4. In a device of the character described, a standard having ears at its upper end, a slotted ring-head pivoted between said ears, and a slotted wire-twisting hub rotatably mounted in said head and removable therefrom.

5. In a device of the character described, a standard having ears at its upper end, a slotted ring-head pivoted between said ears and adapted to tilt from its normal vertical position to one side only, and a wire-twisting hub working in said head and removable therefrom.

6. In a device of the character described, a standard having ears at its upper end, a

slotted ring-head pivoted between said ears and adapted to tilt from its normal position to one side but not to the other, a slotted wire-twisting hub having a counter-bored axially arranged aperture, working in said head, and a wire-end-engaging pin arranged on the heel of said hub.

5 7. In a device of the character described, a suitably supported ring-head, a wire-tightening and twisting hub working there-

in, and a prong secured to the ring-head support for the purpose specified.

In testimony that I claim the foregoing as my invention I hereto subscribe my name, at Galesburg, Illinois, this 10th day of 15 August, 1914.

WILLIAM A. WEBSTER.
